(57) **CLAIM**

The ornamental design for a vehicle interior, as shown and described.

DESCRIPTION

FIG. 1 is a left rear perspective view of a vehicle interior; FIG. 2 is a left front perspective view thereof; FIG. 3 is a right rear perspective view thereof; FIG. 4 is a top plan view thereof, and top perspective view of the floor portion thereof; FIG. 5 is a left side elevational view taken from the section line Figure 7-7 of FIG. 5 thereof; FIG. 6 is a right side elevational view thereof; FIG. 7 is a front elevational view thereof; and, FIG. 8 is a rear elevational view thereof.

In the drawings, the broken lines in the figures depict portions of the article that form no part of the claimed design.
